H. Parker.
his ATTORNEY.

UNITED STATES PATENT OFFICE.

HOWARD PARKER, OF BERLIN, NEW HAMPSHIRE, ASSIGNOR TO BROWN COMPANY, OF PORTLAND, MAINE, A CORPORATION OF MAINE.

CORE FOR ROLLS OF PAPER AND THE LIKE.

1,397,542.

Specification of Letters Patent.

Patented Nov. 22, 1921.

Application filed March 25, 1918. Serial No. 224,412.

To all whom it may concern:

Be it known that I, HOWARD PARKER, a citizen of the United States, and a resident of Berlin, county of Coos, State of New Hampshire, have invented certain new and useful Improvements in a Core for Rolls of Paper and the like, of which the following is a specification.

This invention relates to tubular cores upon which material such as paper can be conveniently wound into rolls. It has especial reference to a reinforcement used at the ends of a core made from pulp stock.

The object of the invention is to provide a strong reinforcement at the points of greatest wear, *i. e.*, the ends of the core, and to securely hold them in position.

Referring to the drawings—

Figure 1 is a perspective view of an end portion of a complete core.

Fig. 2 is a perspective view of the reinforcing sleeve.

Fig. 3 is a central sectional view of one end of a core showing reinforcement applied thereto.

Referring to the drawings—*a* denotes the core proper which is made by winding a continuous sheet of pulp onto a mandrel until a wall of sufficient thickness has been built up, after which the tube is removed from the mandrel and thoroughly dried. *b* denotes a notch in the end of the core to receive a driving dog for the purpose of turning the core either in the winding or unwinding operation. *c* denotes generally a reinforcing bushing fitted to both ends of the core to strengthen the ends so that they cannot be broken down in shipping or handling.

Owing to the fact that there is some variation in the inner diameter of these cores due to uneven shrinkage in the drying operation, the bushing is split as at 5, and its outer end is flanged over as at 6, to protect the ends of the core. The bushing is also cut away opposite the notch in the core, and sufficient metal is left to provide what may be termed radial flanges 7, which may be folded over the sides of the notch to provide a metallic wearing surface for the driving

dog. The edges of these radial flanges are serrated as at 8, so that they may be turned back and driven into the core to lock the bushing in place. In the wall of the bushing, preferably opposite the notch, a prong 10 is formed which projects out from the bushing toward the flanged end thereof and is intended to be driven into the core when the bushing is in place to assist in holding the bushing from accidentally slipping out the end of the core. Preferably this prong is made integrally with the bushing by making a V-shape or U-shape cut through its wall and then bending the point out. It is essential that means, such as the serrated teeth at the ends of the radial flanges, and the additional prong, be provided to make certain that the bushing shall not be disengaged if the core during shipment is either with or without paper wound thereon.

In accordance with the provisions of the patent statutes I have described the principle of operation of my invention, together with the apparatus which I now consider to represent the best embodiment thereof; but I desire to have it understood that the apparatus shown is only illustrative, and that the invention can be carried out by other means.

I claim as my invention:—

A core of the class described comprising in combination with a tube having one end thereof provided with a notch, a normally expanded, split, contractible, protecting bushing of springy sheet metal fitted in the end of said tube, said bushing having opposite notches in the free ends thereof coincident with the notch in the end of said tube, flanges integral with the free ends of said bushing, the ends of said flanges being serrated and folded outwardly and backwardly upon the adjacent edges of said notch in the end of said tube, and an outwardly projecting prong from the wall of said bushing adapted for engagement with the inner wall of said core.

HOWARD PARKER.
